UNITED STATES PATENT OFFICE.

ASA EARL PARMETER, OF LOGANSPORT, INDIANA.

REINFORCED-CONCRETE TIE.

1,096,746.

Specification of Letters Patent. Patented May 12, 1914.

Application filed September 10, 1913. Serial No. 789,092.

To all whom it may concern:

Be it known that I, ASA E. PARMETER, a citizen of the United States, residing at Logansport, in the county of Cass and State of Indiana, have invented new and useful Improvements in Reinforced-Concrete Ties, of which the following is a specification.

This invention is an improved reinforced concrete tie for railroads, the object of the invention being to provide an improved tie of this character which may be manufactured at minimum cost, is exceedingly strong and durable, and which provides means for directly fastening the rails thereon and for adjusting the rails, the invention consisting in the construction, combination and arrangement of devices hereinafter described and claimed.

In the accompanying drawings: Figure 1 is a perspective view of a reinforced concrete tie constructed in accordance with my invention. Fig. 2 is a vertical longitudinal sectional view of the same. Fig. 3 is a plan of the blank from which the facing plate of the tie is constructed. Fig. 4 is a vertical transverse sectional view of my improved reinforced concrete tie on a plane near one of the rails. Fig. 5 is a similar view of the same on a plane between the brace plates. Fig. 6 is a detail perspective view of one of the clamping jaws.

In accordance with my invention I provide a facing plate 1 to cover the body 2 of the tie, this facing plate being preferably made of iron or steel and being formed from a single blank which corresponds in width with the tie and is somewhat longer than the tie so that its ends 3 may be bent at the points indicated by the dotted lines 4 in Fig. 3 and adapted to bear on and cover the ends of the tie. The end portions 3 of the facing plate are formed at their upper sides, where they join the main portion of the facing plate with oblong rectangular openings 5 and the main or top portion of the facing plate is formed with a centrally arranged longitudinal slot 6 which extends to and connects the said openings, and at the center of the said slot, on opposite sides thereof, are notches 7 which form an opening in the center of the facing plate.

A channel plate 8 which is cross sectionally rectangular and the side walls of which are provided with outwardly extending flanges 9 is arranged under the center of the main portion of the facing plate and under

the slot 6 thereof, with its ends coincident with the openings 6 and the flanges 9 of this channel plate are secured to the main portion of the facing plate by means of rivets or other suitable devices 10. Hence the channel plate forms a longitudinal groove or channel wider than and below the slot 6 of the facing plate which extends from end to end of the tie, the sides of the slot 6 formed by the facing plate overhanging opposite sides of the channel and forming flanges 11 and the said flanges are corrugated transversely, the said series of corrugations extending from end to end of the tie and being indicated at 12. It will be understood that the channel plate not only forms a longitudinal channel in the upper side of the tie but also greatly strengthens and reinforces the facing plate below and at the sides of the slot 6 in the latter.

The downturned ends 3 of the facing plate are connected by tie rods 14 which extend from end to end of the tie and through the concrete body thereof and also extend through a pair of transversely arranged brace plates 15 which are in contact with each other and the upper sides of which are provided with outturned flanges 16 which are riveted or otherwise suitably secured to the facing plate as at 17. These brace plates also form a break line across the center of the concrete body of the tie and serve to face the two members or sections of the concrete body of the tie so as to prevent the said concrete members from rubbing against each other under the stresses imposed thereon. The concrete body of the tie is molded so that the tie rods and the channel plate are embedded therein. I also provide rail securing devices for fastening the bases of the rails on the tie. Each of these rail securing devices comprises a bolt 18, a clamp jaw 19, a nut 20 and a lock nut 21. The bolts 18 are arranged vertically with their shanks extending up through the slot 6 of the facing plate and their heads 22, which are square, arranged in the channel of the channel plate and bearing under the flanges 12 from between the sides of the slot 6. The openings 5 and notches 7 enable the bolts to be placed with their heads in the channel, either at the ends of the tie or at the center thereof, as will be understood, and the slot 6 enables the rail securing devices to be adjusted longitudinally of the tie as required.

The clamping jaws 19 are wedge shaped longitudinally so that their inner ends are adapted to bear on the base flanges of the rails, and the said clamping jaws are provided on their under sides with medially arranged downwardly extending tongues 23 which enter the slot 6. The nuts 20 and 21 coact with the heads of the bolts and with the clamping jaws to bind the said parts firmly together and to the flanges 12 of the facing plate and on the base flanges of the rails, so as to securely lock the rails on the tie and the corrugations with which the said flanges 12 are provided strengthen the said flanges and also materially assist in holding the rail securing members in place.

A spring or cushion 23 which is here shown as a fluted spring steel plate, is placed between the brace plates 15 to act as a spring when weight is imposed on the tie and enable the brace plates to move toward each other under such stress, the cushion or spring taking up the shock and permitting the tie to yield slightly to the stress.

Having thus described my invention, I claim:

1. A reinforced concrete tie comprising a concrete body, a facing plate thereon having downturned end portions bearing against the ends of the body, tie rods extending

through the concrete body, embedded therein and secured to the downturned ends of the facing plate and a transversely arranged brace plate in the body of the tie and secured to the facing plate.

35

2. A reinforced concrete tie comprising a concrete body, a facing plate thereon having downturned end portions bearing against the ends of the body, tie rods extending through the concrete body, embedded therein and secured to the downturned ends of the facing plate and a pair of transversely arranged brace plates in the body of the tie and secured to the facing plate.

40

3. A reinforced concrete tie comprising a concrete body, a facing plate thereon having downturned end portions bearing against the ends of the body, tie rods extending through the concrete body embedded therein and secured to the downturned ends of the facing plate, a pair of transversely arranged brace plates in the body of the tie and a cushioning element between said brace plates.

45

In testimony whereof I affix my signature in presence of two witnesses.

ASA EARL PARMETER.
